DISK BRAKE

Edwin R. Evans, Orchard Lake, Mich.

Application July 25, 1938, Serial No. 221,132

26 Claims. (Cl. 188—72)

This invention relates to brakes and particularly disk brakes.

An object of the invention is to secure a flexible disk to a wheel or other rotating member, to arrange a pair of substantially rigid non-rotative plates at opposite sides of such disk, and to provide mechanism for clamping the plates against the disk to apply selective braking pressures, flexibility of the disk assuring its full conformity to the plates.

Another object is to adapt such plates for a limited floating movement along the brake axis, so that they may adjust themselves under all conditions to coact to best advantage with the flexible disk.

A further object is to mount a pressure-applying lever mechanism entirely on said plates, and to adapt one of the plates to take the fulcrum reaction in applying leverage to the other, whereby the forces oppositely applied to the disk are fully equalized.

Other objects are to achieve a much more rapid dissipation of heat than is permitted by brakes now in use, and to so design said disk and plates that efficiency of the brake will not be materially diminished by distortion incident to rapid heat generation due to severe braking.

A further object is to provide a disk brake affording simple and highly accurate manual adjustments to establish proper clearance between the friction-applying and friction-receiving elements under non-braking conditions, and to provide for automatically establishing such a clearance, in case a mechanic fails to complete such an adjustment.

A further object is to establish a highly effective anti-friction relation between a non-revoluble sliding plate or disk member of a brake and an anchorage means for such member, whereby the torque-induced tendency toward heavy friction is largely eliminated in engaging or disengaging such member with a companion revoluble member.

These and various other objects are attained by the construction hereinafter described and illustrated in the accompanying drawings, wherein:

Fig. 1 is a diametrical, vertical, sectional view of the improved brake, as applied to a vehicle wheel.

Fig. 2 is a sectional view of the same, taken in a plane of rotation and on the line 2—2 of Fig. 1, omitting the wheel hub.

Fig. 3 is a sectional view taken in another plane

of rotation, approximately on the line 3—3 of Fig. 1, the hub being again omitted.

Fig. 4 is a horizontal, sectional view taken on the line 4—4 of Fig. 3, primarily showing an arrangement of secondary levers for actuating the brake.

Fig. 5 is a radial, horizontal, sectional view of the brake, taken on the line 5—5 of Fig. 3.

Fig. 6 is a view showing the mounting of one of a pair of primary levers, and is, in part, a section on 6—6 of Fig. 3.

Fig. 7 is a cross sectional view, taken on the line 7—7 of Fig. 6, showing an adjustment means for said primary lever.

Fig. 7A is a cross sectional view, taken on the line 7A—7A of Fig. 6, showing a provision for limiting adjustment.

Fig. 8 is a top plan view of the brake showing how a conduit for an actuating cable is extended from the brake to the frame of a vehicle equipped with the brake.

Fig. 9 is a radial, horizontal sectional view of a slightly modified construction of the brake.

Fig. 10 is a view similar to Fig. 4 but showing hydraulic actuating means for the secondary levers.

Fig. 11 is a diagrammatic view of a thrust-transmitting mounting for a brake-actuating cable, an alternative to the conduit mounting shown in other figures.

In these views, the reference character 1 designates a wheel body integrally formed with a hub 2 and driven through any ordinary connection (not shown) from a live axle 3. The latter projects in the usual manner from a tubular axle housing 4, terminally formed with the customary annular end plate or flange 5 for brake-mounting purposes. Rigidly secured to the outer portion of the body 1 is a ring 6 for carrying a tire-mounting rim (not shown), the securing means being a plurality of studs 7 having heads 8 engaging the inner face of the body 1, and carrying nuts 9 clamping the ring 6 to such body. As shown, a unitary torque-transmitting connection is established between the several studs 7 by a forged, stamped or cast ring 10, coaxial with the wheel.

The studs 7 further function to mount a friction-receiving brake element in the form of a flexible disk 11, stamped preferably from high grade steel. Said disk is mounted on bosses 12, inwardly projecting from the heads 8, and is peripherally formed with tongues 13 outwardly projecting to engage such bosses and clamped thereon by nuts 14 threaded on reduced ends of

the bosses. Preferably the tongues 13 are each formed with a corrugation 13a adjacent to and approximately parallel with the periphery of the disk body to increase freedom of lateral movement of the disk. The bosses 12 space the disk 11 inwardly from the wheel so that friction may be readily applied to both of its faces. Secured to such faces are suitable linings 15 of wear-resistant material, and to assure maximum heat dissipation, such material is preferably a metal or 10 alloy of high friction coefficient.

The lined portion of the disk 11 engages between a pair of non-rotative inner and outer friction-applying annular plates 16 and 17, mounted on the flange 5, to undergo a limited floating movement along the axis of the brake. These plates are substantially non-flexible, being much heavier than the disk 11 and reinforced at their outer margins by annular flanges 18 and at their inner margins by more extensive substantially annular flanges 19. The flanges 18 project oppositely from the plates, whereas both of the flanges 19 project outwardly. The inner plate has a considerably smaller central opening than the outer one and is consequently larger.

To carry the plates 16 and 17, two pairs of pins 20 and 21 are rigidly mounted in the axle flange 5 and project outwardly therefrom, such pins being shouldered to seat against the outer face of said flange and engaged by nuts 22 clamped against the inner face of the flange. The pins 20, which lie above and below the brake axis, slidably receive sleeves 23, each formed between its ends with an exterior annular shoulder 23a and having an externally threaded portion outwardly of such shoulder, for engagement in a socket formed in the inner end of a cylindrical anchorage member 24. The two members 24 are diametrically drilled and tapped to receive and rigidly carry the inner ends of a pair of outwardly projecting, vertical studs 25 having coned outer ends. Rotatable on each of said ends, is a torque-transmitting, dish-shaped member 26, journaled on the corresponding stud 25 through a set of anti-friction balls 27. A ring 28 rigidly carried by and substantially closing the open end of each member 26, is fitted around the corresponding stud 25, coacting with an annular rib 29 on the stud to maintain the assembly and confine a lubricant in the member 26. The radially journaled members 26 engage in pockets 29a, formed in the plate 17 in diametrically opposed relation, by arching its flange 19 outwardly. Such engagement adapts said members to anchor the plate 17 in resistance to torque, while largely eliminating frictional resistance to sliding travel of said plate. The members 26 fit sufficiently freely in the pockets 29a between the opposed walls thereof, to assure clearance of such members from one of such walls. As best appears in Fig. 1, the studs 25 pass to some extent through the socket members 32 and are clamped firmly against such members through screwing of the anchorage members 24 on the sleeves 23. Thus said studs are securely locked against rotation in the members 24. The pins 21 respectively slidably carry sleeves 30 formed, approximately midway of their length, with annular exterior ribs 31. (See Fig. 5.)

The anchorage members 24 and sleeves 30 contact to mount the plate 16 non-rotatively, while affording it a limited travel to and from the plate 17. Thus the plate 16 is formed with sockets 32 (see Fig. 2) communicating with the central

opening of such plate, and disposed to snugly accommodate the members 24 and sleeves 30, the flange 19 of the plate 16 being conformed to said sockets, thus affording such plate ample bearing surfaces on the members engaged in the sockets. By thus mounting the plate 16, it is evident that it is held centered at the brake axis and restrained from rotation, while free to undergo a desired slight axial travel.

A dust-excluding sheet metal cover 33, best seen in Fig. 1, is preferably applied to the brake, such cover having an outer annular shoulder 33a snugly engaging the flange 18 of the plate 16, an inner annular shoulder 33b snugly engaging the flange 5 of the axle housing, a collar 33c extending from said flange to the plate 16 and having the shape of a round-cornered parallelogram (Fig. 3), and a flange 33d projecting from said collar toward the brake axis and forming the central opening 33e of the cover. The flange 33d is apertured to fit over the sleeves 23 and 30, and the cover is held in place through clamping said flange against the shoulders 23a of such sleeves by the members 24.

Jointly mounted in the plates 16 and 17, at approximately opposite sides of their axis, is a pair of pull rods 34 (see Figs. 5 and 6) having nuts 35 thereon, to abut the outer face of the plate 17. Said rods pass freely through the plate 16 and project inwardly considerably beyond such plate. The portions of the rods thus projecting mount a pair of brake-applying levers 36, extending upwardly from said rods and converging toward each other to facilitate their actuation in common. The levers 36 are preferably stampings of U cross section, formed with sockets at their lower ends accommodating fulcruming ball-shaped ends 37 of sleeves 38, slidable on the pull rods 34 but restrained from rotation thereon. The other ends of said sleeves are formed with annular flanges 39, each engageable by two adjusting members 40 and 41. The members 40 are cylindrical nuts, eccentrically drilled and tapped to engage the pull rods 34, and exteriorly threaded to mount collars forming the members 41. Each of the latter is interiorly formed with an odd number of small longitudinal grooves 42, engageable by a detent pin 43 diametrically slideable in the corresponding nut 40, said pin having wedge-shaped ends for lodging in the grooves 42, and having a length adapting one such end to engage the interior wall of the collar between two grooves when the other end is lodged in one of the grooves. Each detent has a depression 44 at its middle, providing a flat surface to bear laterally against the outer end portion of the corresponding rod 34, to restrain the detent pin from rotation. The arrangement is such that the detent pins shuttle back and forth as the collars are being rotatively adjusted on the nuts 40 toward the flanges 39, said detents resisting reverse rotation of the collars. The detents will click as they enter each groove 42 and thus afford audible indications corresponding to definite small increments of adjustment. Each nut 40 has a lug 45 projecting from its inner end and engaging in a marginal recess of the adjacent flange 39, the ends of such recess forming radial shoulders 46, engageable by such lug to limit adjustment of the nut. Each pull rod 34 has a pair of opposed flat faces 47 extending for a considerable portion of the rod length from the outer end of the rod, said faces preventing rotation of the rod in the plate 17, and also preventing rotation of the levers 36 and their fulcruming mem-

bers on said rods. For applying leverage to the plate 16, each lever is formed, a short distance from its fulcrumed end, with a rounded protuberance 48, engaging said plate, and hardened steel disks 49 are recessed in and secured to the plate 16 to receive the thrust of said protuberances.

The levers 36, which may be termed primary levers, are actuatable by a pair of relatively short, duplicate secondary levers 50, of approximately triangular shape, the same being fulcrumed on pins 51 transversely carried by pull rods 52, jointly mounted in the plates 16 and 17. Nuts 53, threaded on the outer ends of said rods, serve to transmit a pull therefrom to the plate 17. Said levers project inwardly from the plate 16 to engage actuating means, and project a lesser distance toward each other to engage the upper ends of the levers 36, being marginally formed with recesses 54 accommodating rounded enlargements 55 terminally formed on the levers 36. The actuating means for the levers 50 consists of a cable 56 anchored to one thereof and a conduit 57 for such cable, terminally carrying a fitting 58 abutting the other. Between the two levers, a spring 59 is coiled on said cable to urge the levers from each other. To accommodate the levers 50, an elongated rectangular opening is formed in the upper portion of the cover 33, the latter forming a wall 60 marginal to such opening, and a closure 61 for such opening being removably attached to such wall as by bolts 62.

Said cable and conduit are freely flexible and the latter is anchored at a point remote from the fitting 58 to the frame 63 of a vehicle, as by a clamping fitting 64. (See Fig. 8.)

The plates 16 and 17 are urged apart by springs 65 (Figs. 4 and 10) coiled on the pull rods 34 and 52, said springs thus tending to normally maintain a suitable clearance between such plates and the friction-receiving disk 11.

In operation of the described brake, when the cable 56 is tensioned, as by depressing a brake pedal (not shown), the portion of the cable extending through the curves of the conduit (see Fig. 8) tends to straighten out and imparts this tendency to the conduit. Since the end of the conduit remote from the brake is anchored to the vehicle frame, the other end of the conduit is advanced, upon tensioning of the cable. Hence a braking operation involves not only a pull transmitted to the lever 50 engaged by the cable, but also a thrust transmitted to the lever 50 engaged by the conduit, and this thrust and pull are equalized through the reaction between the cable and conduit.

As the secondary levers 50, are rocked toward each other due to above described actuation, they actuate the primary levers 36, causing the protuberances 48 to take effect on the plate 16. The reactions of both primary and secondary levers are transmitted to the plate 17 by the pull rods 34 and 52. Consequently the plates 16 and 17 are forced toward each other and the leverage is sufficient that very powerful pressure may be applied. The lined portion of the disk 11 is hence clamped between the plates 16 and 17, and the clamping pressure is a predetermined multiple of the tension applied to the cable 56. Flexibility of said disk is sufficient that it may fully conform itself to the plates, even in case the latter are subjected to considerable distortion by frictional heat. The slightly dished form of the

plates tends to assure that any distortion thereof will similarly affect both.

While both plates 16 and 17 are afforded a limited floating travel axially of the brake, in practice such travel is confined to the plate 17, due to coaction therewith of anti-friction anchorage means, whereas the plate 16 must travel on slide bearings, offering much greater frictional resistance. Provision of the anti-friction members 28 is an important factor in deriving a maximum efficiency from the applied braking effort. This is for the reason that heavy torque is imposed on both plates when the brake is applied and particularly during severe braking, and transmission of such torque to the anchorage members necessarily tends toward heavy frictional resistance to sliding of the plates. If such resistance were not largely eliminated by the members 28, proper modulation of braking would be impossible and a considerable fraction of the effort exerted in applying and releasing the brake would be wasted in overcoming sliding friction. A well modulated control is vital in a vehicle brake under present day, high speed, heavy traffic conditions, and releasing modulation is particularly vital since a braking release, produced by sliding travel, involves overcoming a static coefficient of friction, largely exceeding that of relatively moving parts, as when the brake is applied.

Employment of the described primary and secondary levers and the feature of using both the cable 56 and its conduit 57 to apply a braking force are factors in achieving an unusually high leverage ratio, such a ratio being much more feasible in a disk brake than in drum brakes now employed, since the disk brake employs opposed frictional forces, tending to counteract distortion. As an example of the leverage possibilities of the described brake, a 9 to 1 leverage may be derived from the primary levers, a 3 to 1 leverage from the secondary levers, a 2 to 1 leverage through utilizing both faces of the disk 11, a 2 to 1 leverage due to transmitting the effort through both the cable and conduit, and a foot pedal ratio of at least 2 to 1. Thus the very high total ratio of 216 to 1 may be had. In this connection, it is to be noted that the described brake uses the applied power so effectively as to eliminate any need for a servo or self-energizing control. This is highly desirable, since it is practically impossible to render a brake self-energizing and secure its proper response to a manual control under all road conditions.

Very accurate control of normal clearance between the disk and plates is a feature of the described brake, this being secured by employing the nuts 40 to effect an initial definite adjustment and the collar 41 to effect additional adjustment by small increments determined by lodgment of the detent 43 in the grooves 42 of said collar. The arrangement permits of rapid and accurate compensation for any degree of wear of the linings 15. In adjusting, the mechanic will turn the collars 41 (usually successively) in a direction to feed them inwardly on the nuts 40. Initially, however, said collars and nuts will turn in unison, there being less frictional resistance to turning of the nuts on the threads of the rods 34 than to turning of the collars on the larger diameter nut threads. Engagement of the lugs 45 between the radial shoulders 46 will limit turning of the nuts 40 to an approximate quarter turn, and subsequently

the collars 41 will feed inwardly on the nuts. Inward pressure applied to the sleeves 38, first by the nuts and collars jointly, and subsequently by the collars alone will slide said sleeves along the rods 34 until clearance between the linings 15 is so taken up as to produce a slight drag on the wheels, the sleeves acting on the disk 16 through their fulcrum ends 37 and through the fulcrumed ends of the levers 36. Thereupon the mechanic will apply reverse rotation to the collars 41, sufficient to retract the nuts 40 to their limit of clearance adjustment, determined jointly by the lugs 45 and shoulders 46. Thus the proper working clearance will be quickly and accurately established. The eccentric engagement of the nuts by the rods 34 is utilized to impose on them a gravity tendency to establish proper clearance, their maximum radius portions being above the axes of the rods when clearance is fully taken up. Hence if a mechanic neglects or forgets to adjust the nuts for proper clearance, after inter-engaging the friction linings, the nuts will swing down, when released, and automatically provide for such clearance. If the nuts fail to swing down through gravity alone, their jarring and vibration incident to vehicle travel will induce their descent. The springs 65, as has been pointed out, establish any such clearance of the linings as is permitted by the described adjustment means. Since the lugs 45 of the nuts engage the lowermost shoulders 46, when proper clearance is established, gravity cannot act on the nuts to disturb such clearance.

While the nuts 40 are eccentrically mounted to provide, if necessary, for their rotation by gravity, to establish a certain clearance between plates and disk, it is readily apparent that said nuts may be weighted in any other manner designed to effect their gravity rotation.

The modified construction shown in Fig. 9 differs from the structure already described, in that tongues 13' at outer periphery of the disk 11' are looped so that their ends attaching the disk to the wheel project toward the brake axis, thus providing for increased flexure of such tongues and increased axial play of the disk, as compared to the first-described construction. Also in this construction the inner plate 16' has an outward extension 66 projecting almost to the wheel rim 67 and serving as a heavy shield to exclude dust, gravel and the like from the brake and body of the wheel. The pins 21' which mount the inner plate 16' are headed, as indicated at 70, to prevent outward removal of said plate, and by loosening the nuts 22' which clamp such pins to the axle flange 5', the entire brake remains attached to the wheel, on removing the latter.

Describing now the hydraulic actuating provision illustrated in Fig. 10, the secondary levers 50 and mechanism actuatable thereby does not vary from the previous description. For actuating said levers there is provided a piston 71 working in a cylinder 72, headed at both ends and having a sleeve bearing 73 projecting from one of such ends and slidably mounted in an end wall of the housing 60, 61. Within such housing a yoke 74 extends around the adjacent lever 50 to form an actuating connection from the bearing 73 to a tubular pull rod 75 engaging the remote lever 50. A piston rod 75a actuatable by the piston 71 slides in the bearing 73 and is headed against the lever 50 adjacent to such bearing to impose a thrust thereon. A pipe 76, connected to the outer end of the cylinder, ad-

mits a fluid under pressure between such end and the piston, whereby the levers 50 will be rocked toward each other to actuate the primary levers 36. A spring 77, reacting between the levers 50 and housed partly within the pull rod 75, returns the parts to their normal positions when fluid pressure is relieved.

It is to be noted that the described brake mechanism, in any of its described modifications, permits of clearance adjustment, with considerable greater accuracy and finer increments than has heretofore been the practice. This is for the reason that the faces to be frictionally engaged move directly into and out of such engagement, and it is hence feasible to provide a considerable lesser clearance than is essential for radially acting brakes. Minimum clearance is of course highly desirable from the standpoint of deriving a maximum utility from pedal travel.

Fig. 11 is a diagrammatic illustration of a brake actuating mechanism, substituting a link and pulley arrangement for the conduit 57 here-tofore described.

The levers 79 are substantially the same as the levers 50 of first-described construction, being adapted to rock toward each other in applying a brake. A cable 78 is carried on three pulleys 80, whereof one is mounted at the juncture of a pair of pivotally joined, obtusely divergent link bars 81, while the other two are journaled on the relatively remote ends of such bars. The first-mentioned pulley engages an opposite side of the cable from the two last-mentioned pulleys. One of the relatively remote link bar ends is pivoted on a fixed bracket 82, and the other is pivoted to a thrust rod 84 slidable in a guide 83 fixed in any desired manner (not shown) in proximity to the paired levers. Said cable is connected to one of the levers and the rod 84 bears on the other. When the cable is tensioned, divergency of the link bars is reduced, causing the thrust-bar to apply a force equal and opposite to that applied by the cable. This develops materially less friction than a cable sliding in a conduit.

The invention is presented as including all such modifications and changes as come within the scope of the following claims.

What I claim is:

50. 1. A brake comprising a pair of spaced, substantially rigid non-revolute plates, an annular disk revolute between such plates and flexible to conform itself to the plates, positioning elements for the disk engaging its outer periphery and flexible transversely of the disk to afford it axial movement, and means for actuating the plates toward each other and into frictional engagement with the disk, said plates and disk being correspondingly disked.
55. 2. A brake comprising a pair of spaced non-revolute plates, a disk revolute between such plates, two pairs of pull rods anchored to one of said plates and projecting toward the other plate, levers reacting between one pair of the pull rods and last-mentioned plate to thrust the plates toward each other and into frictional engagement with the disk, and a common means for actuating the levers, reacting through the other pair of pull rods to thrust said plates toward each other.
60. 3. A brake comprising a pair of spaced non-revolute plates, a disk revolute between such plates, two pull rods anchored to one of said plates and projecting toward the other plate, a primary lever reacting between one of the pull

rods and the last-mentioned plate, a secondary lever reacting between the other pull rod and the primary lever, said levers serving to thrust the plates toward each other and into frictional engagement with the disk, and actuating means operative on the secondary lever.

4. A brake comprising a pair of spaced non-revolvble plates, a disk revolvble between such plates, two pull rods anchored to one of said plates and projecting toward the other plate, a primary element reacting through one of said pull rods to apply the plates to the disk, a secondary element reacting between the primary element and the other pull rod to apply the plates to the disk, and actuating means operative on the secondary element.

5. A brake comprising two non-revolvble members, a revolvble member interposed between the non-revolvble members, an anchorage member extending through and effective on one of the non-revolvble members, and an anchorage member for the other non-revolvble member, mounted on the first-mentioned anchorage member and rotatable about an axis substantially radial to the brake.

6. A brake as set forth in claim 5, the non-revolvble members being annular and having pockets opening from their inner peripheries to receive said anchorage members.

7. A brake as set forth in claim 5, the rotatable anchorage member being radially adjustable with respect to the other anchorage member.

8. A brake comprising a pair of spaced non-revolvble plates, a disk revolvble between such plates, a pair of levers, means including fulcrum members for applying said levers at circumferentially spaced points of the plates to engage the plates with the disk, a second pair of levers, respectively actuating the respective levers of the first pair, and means including fulcrum members for applying the second pair of levers at points circumferentially distant from the first mentioned points, to urge one of said plates toward the other.

9. A brake as set forth in claim 8, said fulcrum members being all mounted on one of said plates.

10. A brake comprising a pair of spaced non-revolvble plates, a disk revolvble between such plates, one of said plates being movable to and from the other to take effect on the disk, an anchorage member for such movable plate, rotatable about an axis substantially radial to the brake, a stud substantially radial to the brake and journaling said anchorage member, and means for clamping said stud against the other of said plates to resist rotation of the stud.

11. In a brake, an annular friction-applying plate formed at a periphery thereof with a reinforcing flange, such flange having an approximately U-shaped portion reentrant to said plate and forming a pocket to accommodate anchorage means for such plate.

12. A wheel brake comprising inner and outer non-revolvble members, a member interposed between the non-revolvble members and revolvble with the wheel, the outer non-revolvble member being movable along the brake axis to coact with the inner non-revolvble member in restraining the revolvble member, and an anchorage member for the outer non-revolvble member rotatable about a substantially fixed axis substantially radial to the brake to minimize friction opposing said movement, due to torque.

13. A brake comprising a pair of spaced non-revolvble plates, a disk revolvble between such plates, a tension member anchored to one of said plates and projecting toward the other, a lever mounted on the tension member, and actuating means for the lever, said actuating means and lever each reacting on the other of said plates at angularly spaced points thereof to thrust the plates toward each other and into frictional engagement with the disk.

14. A brake comprising a pair of non-revolvble plates, a disk revolvble between said plates, two tension members secured to one of said plates at points spaced angularly with respect to the brake axis, and two levers respectively fulcrumed on the respective tension members, one of such levers actuating the other, and the other being effective on the other of said plates to thrust the plates toward each other and into engagement with the disk.

15. In a disk type brake, an annular friction-applying plate having a dished form and having a reinforcing and heat-dissipating flange at each of its peripheries.

16. A brake comprising a pair of spaced non-revolvble plates, a disk revolvble between the plates, a pull rod anchored to one of the plates and projecting toward the other plate, a lever reacting between the last-mentioned plate and pull rod to thrust the plates toward each other and into frictional engagement with the disk, a fulcrum member for the lever non-rotatably slid-able on the pull rod, a nut threadable on the pull rod and effective on the fulcrum member to actuate such member toward the plates to regulate clearance between the plates and disk, and means reacting between the fulcrum member and nut to limit turning of the nut to a fraction of a revolution.

17. A brake comprising a revolvble and a non-revolvble member, means for frictionally inter-engaging such members, means yieldably urging such members apart, and means for manually adjusting such members toward each other to regulate their normal clearance, such means including an automatic provision energized independently of relative movement of said members for establishing a predetermined clearance.

18. A brake comprising a revolvble and a non-revolvble member, means for frictionally inter-engaging such members, means yieldably urging such members apart, and means for manually adjusting such members toward each other to regulate their normal clearance, such means including an inertia-responsive provision for establishing a predetermined clearance.

19. A brake comprising a revolvble and a non-revolvble member, means for frictionally inter-engaging said members including a pull rod inter-connecting such members, means yieldably urging said members apart, and an adjusting nut threaded on the pull rod, and effective on one of said members to advance it toward the other to regulate clearance of the members, such nut being weighted to induce a predetermined retractive adjustment from its position interengaging said members.

20. A brake comprising a revolvble and a non-revolvble member, means for frictionally inter-engaging said members, means yieldably urging said members apart, and means for manually adjusting said members toward each other to regulate their normal clearance, including a provision for indicating definite increments of such adjustment, and an automatic provision forming

a part of said manual means and serving to establish a predetermined clearance.

21. A brake as set forth in claim 20, said indicating provision affording audible indications.

22. A brake comprising a pair of spaced non-revolute plates, a disk revolute between said plates, a pair of levers, means including fulcrum members for applying said levers at circumferentially spaced points of the plates to engage the plates with the disk, means acting as levers for actuating said paired levers in common, including a fulcrum provision for applying said lever means at points circumferentially distant from the first-mentioned points to urge one of said plates toward the other, and hydraulic energizing means for said lever means.

23. A brake as set forth in claim 22, said lever means comprising two spaced members respectively taking effect on the respective levers of said pair, said hydraulic means being jointly carried by said members.

24. A brake comprising an annular revolute member, an annular non-revolute member movable axially of the brake to exercise a braking effect on the revolute member and having a pocket opening from its inner periphery, an anchorage member disposed in said pocket and rotatable therein about an axis substantially

radial to the brake, a fixed support for said anchorage member extended through the revolute member, and an element rigidly mounted and adjustable substantially radially upon said support and forming a journal for said anchorage member.

25. A brake comprising a revolute and a non-revolute member relatively movable along the axis of the brake and both of substantially a disk 10 form, means yieldably urging said members apart, and means for manually adjusting said members toward each other to regulate their normal clearance, including a provision for indicating definite increments of such adjustment and 15 an automatic provision for establishing a predetermined clearance.

26. A brake comprising a revolute and a non-revolute member, means for frictionally inter-engaging said members, means yieldably urging 20 such members apart, and means for manually adjusting such members toward each other to regulate their normal clearance, such means including an automatic provision for establishing a predetermined clearance, such provision including an inertia-responsive element and means 25 for resisting flutter of such element.
